(57) **CLAIM**

The ornamental design for a shower curtain rod head as shown and described.

DESCRIPTION

FIG. 1 is a front, right and top perspective view of a shower curtain rod head showing my new design;

FIG. 2 is rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a front, right and top perspective view thereof in a use state.

The broken lines shown in FIG. 2 and FIG. 8 depict portions of the shower curtain rod head that form no part of the claimed design. The broken lines shown in FIG. 9 depict environmental structures of the shower curtain rod head that form no part of the claimed design.
